FUEL MIXER

Joseph F. Gohn, Grosse Ile, Mich.

Application October 26, 1945, Serial No. 624,810

7 Claims. (Cl. 48—180)

1

My invention relates to a new and useful improvement in a gaseous fuel mixer and more particularly to a mixer that is readily mounted between a carburetor and intake manifold without interference with the present parts of an internal combustion engine.

It is an object of the present invention to provide a mixer of this kind which operates through the suction of an internal combustion engine to break up all liquid globules into gaseous vapors and thoroughly mixing it with air passing therethrough from carburetor to the intake manifold.

Another object of the present invention is to provide a mixer which will readily revolve and break up any liquid globules passing therethrough and providing a central passageway through the mixer for passage of gaseous mixtures therethrough and which serves as an axis for the revolving mixer.

A further object of the present invention is to provide a mixer with a rotary member having a plurality of angled passageways therethrough connecting with similarly directed passageways in a stationary member which serves to jet the gaseous fluid as it is forced therethrough by the rotating member into the intake manifold.

A still further object of the present invention is to provide a mixer of this class which is simple in structure, economical of manufacture, durable, compact, highly efficient in use and easily installed.

Other objects will appear hereinafter.

It is recognized that various modifications and changes may be made in the detail of structure illustrated and it is intended that such shall be embraced within the scope of the claims which form a part hereof.

Forming a part of this specification are drawings in which,

Fig. 1 is a central vertical cross-sectional view of the invention showing it installed between carburetor and intake manifold,

Fig. 2 is a view taken along line 2—2 of Fig. 1,

Fig. 3 is a sectional view taken along line 3—3 of Fig. 2,

Fig. 4 is a fragmentary bottom plan view of the invention.

Shown in the drawings is a plate 10 which is interposed in the connection between the carburetor outlet conduct 11 and the neck 12 of an intake manifold and is secured therebetween by the bolts 13. The plate 10 is provided with a circular recess or well 14 which is in direct communication with the outlet side of the carburetor, and provides a thin wall 15 on the in-

2

take manifold side. Positioned in the recess or well 14 is a disc 16 of slightly smaller diameter than the recess or well 14 to permit free rotation of the disc therein. Centrally located in the disc 14 is an axially directed passageway 17 which communicates with a similarly directed passageway 18 formed in the wall 15 of plate 10. Grouped radially about the center passageway 17 are a plurality of passageways 19. These passageways 19 are grouped in concentric circles about the passageway 17, and a similar number of passageways are formed in each concentric circle. The passageways are uniformly spaced-apart in each concentric circle, and further in each circle the passageways are staggered relative to the preceding circle when counting outwardly from the inner circle. Thus the passageways on the intermediate row will be set rearwardly to respective passageways on the adjacent inner row relative to the direction of rotation of the disc. Similarly the outer or succeeding concentric circle of passageways will be set rearwardly to respective passageways on the intermediate row relative to the direction of rotation of the disc. The radial angles between respectively staggered passageways in the inner circle with the intermediate circle, and between the intermediate circle and outer circle are equal. Each of the passageways 19 in each concentric circle are directed at an angle from the top to the bottom of the disc, and all are directed at the same angle. Each of the passageways 19 are further directed tangent to its concentric circle. A similar number of passageways 20 are formed in the thin wall section 15 of the plate 10. The passageways 20 are arranged in identical manner to those in the disc 14.

Formed in the periphery of the disc 16 are grooves 21. The grooves 21 are equally spaced-apart and are formed at an inclined angle identical to the angle of the passageways 19.

Extending upwardly from the top surface of the disc 16 is an inverted V-shaped ridge 22 that extends circumferentially about the disc located between the last concentric row of passageways and the grooves 21. A similar ridge 23 is formed on the bottom face of the disc 16 and is similarly located.

In operation as the engine is cranked creating a suction for drawing the fuel mixture from the carburetor into the combustion chamber the mixture as it passes downwardly through the passageway will due to its angle and direction cause the disc to rotate, and as it rotates it will force 55 the mixture through the passageways 20 to be

3

ejected into the intake manifold as a fine spray. Any liquid globules entering the passageway 17 will become broken up and atomized as it passes into the intake manifold. By the arrangement of the passageways 17 and 20 the fuel mixture is ejected to follow a circular or rotary path which further tends to thoroughly mix the fuel before passing into the combustion chamber of the engine. The fuel mixture passing downwardly through the central passages 17 and 18 serves to provide an axis for the disc as it rotates. Also the fuel mixture passing downwardly in the grooves 21 acts as a cushion and lubricant for the rotating disc 16, between its peripheral sides and the sides of the well 14.

To prevent the rotating disc from bobbing up and down in the well 14 due to any undue vibration of the internal combustion engine there is provided a thin plate 24 secured between plate 10 and carburetor and which extends over the peripheral edge of the disc to prevent the disc 16 from moving outwardly from the well.

What I claim as new is:

What I claim as new is:

1. A fluid fuel mixer of the class described, comprising: a plate adapted to be interposed between an intake manifold and the outlet of a carburetor and having a well formed in one face thereof in line with said intake and outlet; a bottom for said well; a disc loosely positioned in said well and resting on said bottom for free rotation thereon, said disc having a plurality of passageways formed therethrough and extending from face to face thereof, said passageways being inclined to the axis of said disc for effecting a rotation of said disc upon delivery of fluid fuel under pressure therethrough, said bottom having a plurality of passages formed therethrough, the passages in said disc being adapted for movement into and out of registration with the passages in said bottom upon rotation of said disc in said well.

2. A fluid fuel mixer of the class described, comprising: a plate adapted to be interposed between an intake manifold and the outlet of a carburetor and having a well formed in one face thereof in line with said intake and outlet; a bottom for said well; a disc loosely positioned in said well and resting on said bottom for free rotation thereon, said disc having a plurality of passageways formed therethrough and extending from face to face thereof, said passageways being inclined to the axis of said disc for effecting a rotation of said disc upon delivery of fluid fuel under pressure therethrough, said bottom having a plurality of passages formed therethrough, the passages in said disc being adapted for movement into and out of registration with the passages in said bottom upon rotation of said disc in said well, the passages in said bottom being inclined to the axis thereof at the same inclination as the passages formed through said disc.

3. A fluid fuel mixer of the class described, comprising; a plate adapted to be interposed between an intake manifold and the outlet of a carburetor and having a well formed in one face thereof in line with said intake and outlet; a bottom for said well; a disc loosely positioned in said well and resting on said bottom for free rotation thereon, said disc having a plurality of passageways formed therethrough and extending from face to face thereof, said passageways being inclined to the axis of said disc for effecting a rotation of said disc upon delivery of fluid fuel under pressure therethrough, said bottom having a plurality of passages formed therethrough, the

4

passages in said disc being adapted for movement into and out of registration with the passages in said bottom upon rotation of said disc in said well, the passages in said bottom being inclined to the axis thereof at the same inclination as the passages formed through said disc, there being an axially, centrally located passage formed through said bottom and through said disc and permanently in registration with each other.

4. A fluid fuel mixer of the class described, comprising: a plate adapted to be interposed between an intake manifold and the outlet conduit of a carburetor and having a well formed in one face thereof in line with said intake and outlet and of substantially the same diameter as said conduit; a bottom for said well; a disc loosely positioned in said well and resting on said bottom for free rotation thereon, said disc having a plurality of concentric rows of circumferentially spaced apart passageways formed therein, the passageways in adjacent rows being radially offset from each other, the axis of said passageways being inclined to the axis of said disc and extending from face to face thereof, said bottom having corresponding circumferentially spaced apart passageways in concentric rows, the passageways in said bottom being inclined to the axis thereof at the same inclination of the corresponding passageways in said disc and adapted for forming an extension of the passageways in said disc upon registration of said passageways therewith to provide a passageway for passage of fluid fuel drawn therethrough and projection of the fluid fuel mixture into the intake manifold in a circulatory motion.

5. A fluid fuel mixer of the class described, comprising: a plate adapted to be interposed between an intake manifold and the outlet conduit of a carburetor and having a well formed in one face thereof in line with said intake and outlet and of substantially the same diameter as said conduit; a bottom for said well; a disc loosely positioned in said well and resting on said bottom for free rotation thereon, said disc having a plurality of concentric rows of circumferentially spaced apart passageways formed therein, the passageways in adjacent rows being radially offset from each other, the axis of said passageways being inclined to the axis of said disc and extending from face to face thereof, said bottom having corresponding circumferentially spaced apart passageways in concentric rows, the passageways in said bottom being inclined to the axis thereof at the same inclination of the corresponding passageways in said disc and adapted for forming an extension of the passageways in said disc upon registration of said passageways therewith to provide a passageway for passage of fluid fuel drawn therethrough and projection of the fluid fuel mixture into the intake manifold in a circulatory motion, there being formed centrally through said bottom an axially directed passage in alignment with a centrally formed, axially directed passage projected through said disc.

6. A fluid fuel mixer of the class described, comprising: a plate adapted to be interposed between an intake manifold and the outlet conduit of a carburetor and having a well formed in one face thereof in line with said intake and outlet and of substantially the same diameter as said conduit; a bottom for said well; a disc loosely positioned in said well and resting on said bottom for free rotation thereon, said disc having a plurality of concentric rows of circumferentially

spaced apart passageways formed therein, the passageways in adjacent rows being radially offset from each other, the axis of said passageways being inclined to the axis of said disc and extending from face to face thereof, said bottom having corresponding circumferentially spaced apart passageways in concentric rows, the passageways in said bottom being inclined to the axis thereof at the same inclination of the corresponding passageways in said disc and adapted for forming an extension of the passageways in said disc upon registration of said passageways therewith to provide a passageway for passage of fluid fuel drawn therethrough and projection of the fluid fuel mixture into the intake manifold in a circulatory motion, there being formed centrally through said bottom an axially directed passage in alignment with a centrally formed, axially directed passage projected through said disc, said disc having a plurality of grooves formed in its periphery extended angularly to the axis of said disc.

7. A fluid fuel mixer of the class described, comprising: a plate adapted to be interposed between an intake manifold and the outlet conduit of a carburetor and having a well formed in one face thereof in line with said intake and outlet and of substantially the same diameter as said conduit; a bottom for said well; a disc loosely positioned in said well and resting on said bottom for free rotation thereon, said disc having a plurality of concentric rows of circumferentially spaced apart passageways formed therein, the passageways in adjacent rows being radially offset from each other, the axis of said

passageways being inclined to the axis of said disc and extending from face to face thereof, said bottom having corresponding circumferentially spaced apart passageways in concentric rows, the passageways in said bottom being inclined to the axis thereof at the same inclination of the corresponding passageways in said disc and adapted for forming an extension of the passageways in said disc upon registration of said passageways therewith to provide a passageway for passage of fluid fuel drawn therethrough and projection of the fluid fuel mixture into the intake manifold in a circulatory motion, there being formed centrally through said bottom an axially directed passage in alignment with a centrally formed, axially directed passage projected through said disc, said disc having a plurality of grooves formed in its periphery extended angularly to the axis of said disc, and means overlying said disc for preventing displacement of said disc from said well.
